UNITED STATES PATENT OFFICE

166,725

TABLE AND SEAT UNIT

Joseph W. Watson, Uvalde, Tex.

Application January 24, 1949, Serial No. 428

Term of patent 7 years

(Cl. D33—14)

To all whom it may concern:

Be it known that I, Joseph W. Watson, a citizen of the United States of America, residing at Uvalde, State of Texas, have invented a new, original, and ornamental Design for Table and Seat Unit, of which the following is a specification, reference being had to the accompanying drawing, forming a part thereof.

The drawing figure is a perspective view of a table and seat unit, showing my new design.

I claim:

The ornamental design for a table and seat unit, substantially as shown.

JOSEPH W. WATSON.
